(57) **CLAIM**

The ornamental design for an animal ear covering, as shown and described.

DESCRIPTION

FIG. 1 is a front elevation view of an animal ear covering showing my new design, the opposite side being a mirror image of the shown;

FIG. 3 is a left side elevation view thereof;

FIG. 3 is a right side elevation view thereof;

FIG. 4 is a top plan view thereof;

FIG. 5 is a bottom plan view thereof;

FIG. 6 is a left, front perspective view thereof; and,

FIG. 7 is a right front perspective view thereof.

The broken lines in FIG. 7 of the drawings depict environmental subject matter only and form no part of the claimed design.
